UNITED STATES PATENT OFFICE.

PHILIP MICHEL, OF STAPLETON, NEW YORK.

WINDOW-SHADE.

SPECIFICATION forming part of Letters Patent No. 290,698, dated December 25, 1883.

Application filed October 31, 1883. (No model.)

To all whom it may concern:

Be it known that I, PHILIP MICHEL, a citizen of the United States, and a resident of Stapleton, in the county of Richmond and State of New York, have invented certain new and useful Improvements in Window-Shades, of which the following is a specification.

This invention relates to the construction of window-shades; and it consists of a simple and inexpensive method of finishing the ends thereof with or without the addition of ornaments or fringes, as shown in the accompanying drawings, of which—

Figure 1 is an edge view of the lower part of a shade with my improvement. Fig. 2 is a front view of the same. Fig. 3 is a sectional view of the binder, taken on line $x-x$ of Fig. 2. Fig. 4 is an end view of the binder as used without the additional ornament or fringe.

The same letters refer to the same parts throughout.

In my improvement the lower end of the shade A, which may be made of any suitable material, is simply folded, as shown at b , Figs. 1 and 2, upon itself, without stitching or sewing, which injures the texture of the shade. Upon the enlargement or fold thus made I slide a wooden binder, B, which is provided with a groove, b' , so formed as to hold the binder upon the folded end of the shade.

When it is desired to add a fringe or other ornament, as C, the same should be woven with a cord or enlargement at the edge, as shown at

c , and the binder B is then provided with two grooves, as shown at $b' c'$, Fig. 3, the one of which grooves permits the binder to be slid upon the shade, and the other similarly permits the fringe to be slid into the binder.

The binder B is best constructed of two pieces of wood, properly formed, as shown in Figs. 3 and 4, and glued or otherwise secured together, thus forming a cheap and durable means of finishing the ends of window-shades.

Having thus described my invention, what I claim, and desire to secure by Letters Patent, is—

1. In a window-shade, the wooden binder B, when provided with the two grooves b' and c' , as and for the purposes herein shown and described.

2. The combination of the wooden binder B with the shade A and ornament C, when the parts are made removable, as herein shown and described.

3. In a window-shade, the fringe C, provided with an enlargement, c , of its upper edge, as and for the purpose herein shown and set forth.

Signed at New York, in the county of New York, and State of New York, this 30th day of October, A. D. 1883.

PHILIP MICHEL.
